ISIDOR B. ROSS, OF NEW YORK, N. Y., ASSIGNOR TO ADJUSTO SHOE LACE COMPANY, INCORPORATED, OF NEW YORK, N. Y., A CORPORATION OF NEW YORK.

ADJUSTABLE TIP FOR SHOE AND CORSET LACES.

1,411,746.

Specification of Letters Patent.

Patented Apr. 4, 1922.

Application filed March 7, 1921. Serial No. 450,181.

To all whom it may concern:

Be it known that I, ISIDOR B. Ross, a citizen of the United States, residing at New York city, borough of Manhattan, in the 5 county and State of New York, have invented a certain new and useful Adjustable Tip for Shoe and Corset Laces, of which the following is a specification.

This invention is an adjustable tip adapted 10 more particularly for use on shoe and corset laces, and when associated therewith is intended to permit of variation in the length of the lace, thereby obviating the necessity of employing laces of undue 15 length.

It is the practice to make shoe and corset laces of different lengths and in purchasing such laces, it is usually found that the lace 20 is longer than necessary and that after tying the lace in a knot, lengthy free ends must be tucked in.

The object of this invention is to provide a tip which may be adjusted longitudinally of the lace, whereupon the lace may be cut 25 to the desired length and the tip firmly secured against movement on the lace or inadvertent displacement therefrom.

In one of its preferred practical forms, the tip of the present invention is made in 30 two parts. One part is in the form of a tubular member through which the lace extends. The end of the lace is adapted to be cut off substantially flush with one end of the tubular member, whereupon the sec- 35 ond or solid part of the tip is brought into cooperative relation with the tubular member to secure the lace in position within the tubular member. The solid part of the tip embodies a threaded shank adapted to be 40 screwed into the core of the lace and cut or form a thread directly in the lace, so as to expand and firmly bind the lace to the tubular member.

An important part of this invention re- 45 sides in so forming the tubular part that semispherical domes would project from the inner surface thereof, so that when the shank of the solid part is screwed into place, it will not only firmly bind the lace within 50 the tubular part, but will cause a positive locking action through cooperation with the semi-spherical domes. If these domes were

not employed, it would be practically impossible to firmly secure the lace to the tubular part against pulling away when strain is 55 placed on the tip. In any event, the threaded shank of the solid member would have to be made so tight, in the absence of the domes, that it would so badly cut the lace when screwed into the tubular member as 60 to cause the end of the lace to be weakened, whereby it might be easily torn from the remainder thereof. However, when the domes are employed, a tight locking engagement results without injury to the lace. The 65 domes preferably present a smooth surface to the lace so as to permit the tubular part to be slid longitudinally of the lace without any injury whatsoever thereto. If sharp 70 points or threads were formed on the interior of the tubular part, such sliding movement of the tubular part would result in cutting or damage to the lace, thereby not only weakening the lace, but spoiling its appearance.

Features of the invention, other than those 75 specified, will be apparent from the herein-after detailed description and claims, when read in conjunction with the accompanying drawings.

The accompanying drawings illustrate 80 one practical embodiment of the present invention, but the construction therein shown is to be understood as illustrative, only, and not as defining the limits of the invention.

Figure 1 shows the tip of the present in- 85 vention associated with the lace, a portion of the tip and part of the lace being shown in section.

Figure 2 shows the two parts of the tip partially removed with one part of the tip 90 in section and the remainder of the structure in elevation.

Figure 3 is an elevation showing parts of the tip removed on the end of a lace; and,

Figure 4 is a central section perspective of 95 the tubular part of the tip.

Referring to the drawings, 5 designates a lace and 6 and 7 the two separable parts of the tip. The part 6 is of tubular form having an interior diameter substantially 100 equal to the diameter of the lace. The part 7 is preferably made solid and is provided with a screw threaded shank 8, the free end of which is tapered to a point 9. The over-

all diameter of the shank is slightly less than the inner diameter of the tubular part 6, and at the base of such shank, the solid part 7 is formed with a tapering section 10. 5 The corresponding end of the tubular part 6 is correspondingly shaped as shown at 10^a.

In affixing the tip of the present invention to a lace in such manner as to impart the desired length to the lace, the lace is 10 passed through the tubular part 6, while the latter is disassociated with the solid part 7 of the tip and such tubular part of the tip is slid longitudinally along the lace, for example, into the dotted line position 15 shown in Figure 2. The lace is then cut to the proper length, whereupon the tubular member is slid toward the cut end and into the full line position of Figure 2, wherein the cut end of the lace will be substantially 20 flush with the end of the tubular member. The pointed end 9 of the shank 8 is now forced into the center or core of the lace and after such entry is made, the solid part 25 7 of the tip is rotated, so as to screw the shank 8 into the lace, after the manner shown in Figure 2, wherein the shank 8 is shown as having been screwed in substantially half its length.

The rotation of the solid part 7 is continued until the stem has been screwed completely into the lace. This operation of screwing the stem into the lace effects a 30 forming of threads in the body of the lace and simultaneously expands the lace within 35 the tubular part 6, so that it will have a tight frictional gripping relation with the inner surface of said tubular part. Moreover, at the conclusion of such operation, the tapered section 10 of the solid part 7 40 will cooperate with a correspondingly formed surface at the adjacent end of the tubular part in causing the lace to be flared outwardly and tightly gripped between these 45 cooperating parts, as clearly shown in Figure 1.

The interior of the tubular part 6 is in practice made perfectly smooth, and when this structure is followed, some means is required to preclude the tip from falling 50 from the end of the lace, because even though the lace is tightly forced against the interior of the tubular part by the screw shank 8, the smoothness of the bore of the tubular part, together with the soft character 55 of the lace structure, make it impossible to securely attach the tip to the lace without the employment of further and efficient binding means. In other words, friction alone cannot be depended upon to 60 hold the parts in assembled relation.

While screw threading the interior of the tubular part would give the desired gripping action, such screw threading is entirely impractical, since it would so cut the lace 65 as to not only seriously weaken it, but to

also mar or catch the threads of the lace when the tubular member is slid longitudinally thereof, prior to attachment. Accordingly, and after much experimentation, I have found that the efficient manner of assuring proper binding of the lace within the tubular part is to employ in conjunction with the screw threaded shank, semi-spherical domes on the interior of the tubular part. These domes are designated in the 70 drawing by the reference character 11 and may be conveniently formed by forming depressions on the exterior surface of the tip which results in impressing the inner surface of the tubular part after the manner clearly shown in Figures 1, 2 and 4. These semi-spherical domes are made relatively small and may be in any number desired, and placed in any relative positions about the tubular part. However, I have 75 shown only three for the purpose of illustration, and it has been demonstrated by practice that two or three are thoroughly efficient in maintaining a proper locking or clamping relation between the parts. The 80 semi-spherical domes, in operation, have the function of forcing the wall of the lace between successive threads of the threaded shank 8, after the manner clearly shown in 85 Figure 1, so that when the parts are in assembled relation, they will be firmly locked or interfitted together and will not depend entirely upon friction to maintain the integrity of the structure.

Through the employment of the present 90 invention, on corset and shoe laces, such laces may be readily cut to any length desired and a tip firmly secured in place on the cut end without the employment of any tools and in a simple and expeditious manner. The tip may be readily removed, for 95 any purpose if desired, but its parts are so bound together by the lace structure that inadvertent displacement of the parts of the tip is precluded.

Of marked practical importance is the 100 fact that the tip of the present invention is unusually simple in construction, and can be manufactured at a nominal cost. The parts may be readily stamped up in quantity 105 production through the employment of conventional machinery, and, because there is no actual engagement between the screw threaded shank of the solid part 7 and the interior of the tubular part 6, great nicety 110 in fitting these parts is not required. They can be made by quantity production in substantially cooperating sizes and will be 115 found to properly cooperate because of the ability of the lace to compensate for slight 120 discrepancies in structure or fit. It will be 125 noted from Figure 1 that when the parts are assembled the end of the lace into which the threaded shank is screwed is formed 130 into a substantially tubular section coaxial

with the threaded shank and the tubular part 6 of the tip and this tubular section of the lace partakes of a position between the metallic parts of the tip so that there is 5 no cutting action such as would result if a fabric were brought between a metal to metal contact.

Having thus fully described the invention, what I claim as new and desire to set 10 cure by Letters Patent is:

1. A tip for laces embodying a tubular portion having a smooth interior, through which one end of the lace is adapted to be passed so as to extend through substantially 15 the entire length of the tubular portion, a plurality of smooth projections extending from the inner surface of the tubular portion, and a threaded portion adapted to be screwed into the lace to expand the lace 20 within the tubular portion for substantially the entire length of the latter and form that portion of the lace within the tubular portion of the tip into a cylindrical section substantially coaxial with the tubular portion 25 and threaded portion of the tip, with the threads of the threaded portion cooperating with the projections to lock the tip against inadvertent displacement from the lace.

2. A tip for laces embodying a tubular portion having a smooth interior, through which one end of the lace is adapted to be passed, a plurality of smooth faced substantially semi-spherical domes extending from the inner surface of the tubular member, and a threaded portion adapted to be screwed into the lace to expand the lace within the tubular portion for substantially 35 the entire length of the latter and form that portion of the lace within the tubular portion 40 of the tip into a cylindrical section substantially coaxial with the tubular portion and threaded portion of the tip, with the threads of the threaded portion cooperating with the semi-spherical domes to lock the 45 tip against inadvertent displacement from the lace.

3. A lace attachment embodying a female tubular member having a non-threaded inner surface and adapted to receive and 50 house the end of a lace which extends through substantially the entire length of the tubular member and a plurality of protuberances extending inwardly from said inner face, in combination with a male member 55 having an irregular exterior adapted to be forced centrally into the end of the lace when housed as specified, whereby the lace is expanded and held securely gripped through the cooperating action between the 60 protuberances on the inner face of the female member and the irregular exterior surface of the male member.

4. A lace attachment embodying a female tubular member having a non-threaded 65 inner surface and adapted to receive and

house the end of a lace, said female tubular member being provided interiorly with spaced domes, in combination with a male member having a threaded exterior adapted to be centrally forced into the end of the 70 lace when housed as specified, whereby the lace is expanded and held securely gripped through the cooperating action between the domes on the inner face of the female member and the threaded exterior surface of the 75 male member.

5. A tip for laces embodying a tubular portion into which one end of a lace is adapted to be introduced, so that the lace will extend through substantially the entire 80 length of the tubular portion, and a male member provided with a threaded shank and of lesser diameter than the internal diameter of the tubular portion and adapted to be screwed into the centre of that portion 85 of the lace housed within the tubular portion for the purpose of forcing the threaded shank longitudinally into the lace, whereby that portion of the lace which receives the threaded shank is formed into a tubular con- 90 form and expanded into tight frictional engagement with the inner surface of the tubular portion.

6. A tip for laces embodying a tubular sleeve into which one end of a lace is adapted to be introduced, so that the lace will extend for substantially the entire length of the sleeve, and a member provided with a threaded shank adapted to be screwed into the end of the lace after it has been positioned in the sleeve for the purpose of extending the lace within the sleeve, said threaded shank being free from engagement with the sleeve and being held in position by the threads which it automatically forms 105 in the interior of the lace.

7. A tip for laces embodying a tubular sleeve provided with a smooth interior, from which projects a plurality of domes, a male member provided with a head, of larger 110 cross section than the interior cross section of the sleeve, and having a threaded shank of less diameter than the cross section of the sleeve, whereby, when the lace is introduced into the sleeve so as to extend entirely therethrough, the threaded shank may be screwed into the interior of the lace, without engagement with the sleeve, to expand the lace within the sleeve and cause the head of the male member to grip the end of the lace, 115 between the end of the sleeve and the base of the head.

8. A tip for laces embodying a female member in the form of a sleeve provided with a smooth interior from which projects 120 inwardly a plurality of convex domes, and into the interior of which sleeve a lace is adapted to be introduced so as to extend entirely through the sleeve, in combination with a male member embodying a head, a 125 130

threaded shank, and a tapering portion intermediate the head and the shank, whereby the threaded shank may be screwed into the centre of the lace for the purpose of imparting to that portion of the lace within the sleeve a tubular shape and expanding said portion of the lace within the sleeve, and for

causing the tapering portion of the male member to seat into the end of the sleeve and tightly clamp the end of the lace. 10

In testimony whereof, I have signed my name to this specification.

ISIDOR B. ROSS.
